UNITED STATES PATENT OFFICE.

AUGUST PITTELKOW, OF CHICAGO, ILLINOIS, ASSIGNOR TO ERIE CAN COMPANY, OF CHICAGO, ILLINOIS, A CORPORATION OF ILLINOIS.

LOCK FOR BOX LIDS AND THE LIKE.

Application filed October 17, 1923. Serial No. 669,043.

To all whom it may concern:

Be it known that I, AUGUST PITTELKOW, a citizen of the United States, residing at Chicago, in the county of Cook and State 5 of Illinois, have invented a certain new and useful Improvement in Locks for Box Lids and the like, of which the following is a specification.

My invention relates to locks for box lids 10 and the like, and is of the type employed to prevent accidental opening during transit and at the same time permit the box to be readily opened at any time without the aid of the key. My device is particularly applicable to metal boxes in which inflammable articles are shipped, for example, moving picture films. The object of the invention 15 is to provide a lock of this character which shall be of simple construction, secure when 20 in use and readily unlocked when a deliberate attempt is made to unlock it.

I accomplish my object by the construction illustrated in the accompanying drawing in which—

25 Figure 1 is a perspective view of the box with the invention applied to it. In full lines the locking device is shown in locked condition.

30 Figure 2 is a perspective view showing the lock in position to release the hasp.

Figure 3 is a perspective view of the part which I shall term the "arch" and which is analogous to the staple of an ordinary hasp lock.

35 Figure 4 is a perspective view of the block which effects the locking action.

Like numerals denote like parts throughout the several views.

40 The box 1 has a lid 2 which is hinged at the back. At the front is a hasp 4 which is hinged at its upper end to the front of the box lid. It has an aperture 6 which is elongated and accommodates an arch 8 rigidly secured to the front wall of the box 45 in such position that the hasp may fit over it when lowered to the full line position shown in Figure 1. While the shape of the arch may be varied to a certain extent, in the form shown it has feet 10 at the ends 50 by which it may be spot welded, soldered, riveted or otherwise secured to the front of the box.

According to the preferred design the aperture or slot 6 is rectangular and but 55 slightly larger than the raised portion of

the arch so that when the hasp is lowered to locked position the arch will be approximately co-extensive with the aperture.

Between the ends of the arch are notches 12, one on one side and one on the other, 60 thus, according to the present design, imparting a zigzag appearance to the arch.

A block 14 forms the locking element. It has a slot 16, the length of which is slightly greater than the full width of the 65 arch. Consequently the block is freely slideable along the arch but is permanently secured to it. The intermediate portion 18 of the arch between the notches 12 is slightly shorter than the length of slot 16, and the consequence is that by proper manipulation the block may be rotated sufficiently 70 to bring it entirely in front of the aperture in the hasp, thus permitting the hasp to be released. 75

In operation let it be assumed that the box lid 1 has been lowered to closed position shown in Figure 1. The hasp 4 at first will occupy a position such as the one shown in dotted lines in Figure 1. To lock the box 80 the operator will first shift lock 14 along the arch 8 to mid position and then rotate it to vertical position, portions of the block entering the notches 12 as shown in Figure 85 2. This makes it possible for the operator to lower the hasp over the block and arch to the position shown in Figure 2. When this has been accomplished the operator rotates the block back again so that it will come crosswise of aperture 6. As the length 90 of the block is greater than the width of the aperture it is evident that the hasp will now be locked. The operator may now release the block, that is, let it drop by gravity to the lower end of the arch whereupon it 95 will hang in vertical position as shown in Figure 1. This is the final locked position and obviously gravity will tend to maintain the block in this position. Even though the box be handled roughly or placed in various 100 positions there is little danger of the block permitting the hasp to be freed.

When it is desired to unlock the box the reverse operation is performed. The operator simply lifts the block to approximately the mid position of the arch and then rotates it approximately 90 degrees to bring the plane of the block in alignment with and in front of the aperture in the hasp. Consequently it will be seen that the 110

operation of locking and unlocking is extremely simple and requires no detached key of any kind and yet when the box is locked it will safely remain so.

5 Having thus described my invention what I claim as new and desire to secure by Letters Patent is:

1. A hasp lock having a hasp with a slot arranged longitudinally and having uninterrupted parallel sides and two locking elements, one of which constitutes an arch projectable through the slot in the hasp and the other constitutes a locking block having an aperture through which the arch 10 passes, one of said locking elements having a plurality of oppositely disposed indentations of sufficient depth to enable the locking block to be rotated about an axis perpendicular to the plane of the hasp to a 15 position substantially in line with the arch to enable the locking block to occupy either of two positions, viz crosswise of the slot for locking the hasp or lengthwise of the slot for releasing the hasp.
2. A hasp lock having an arch, a hasp apertured to fit over it, and a block whose width is greater than the width of the aperture in the hasp and whose thickness is less than the width of the aperture, said block 20 being permanently connected to the arch and loosely mounted on it, and the arch having indentations in the side for permitting the block to be rotated to a position

entirely in front of the aperture for releasing the hasp.

3. A hasp lock having a hasp with an aperture in it, an arch which in the main is approximately of the same width as the aperture, and a block whose width is greater than the width of the aperture, and whose thickness is less than the width of the aperture, the block being slidable lengthwise of the arch, and the arch having notches in the side whereby the block is also rotatable on the arch to enable it to lie wholly 40 in the front of the aperture for releasing the hasp.

4. The combination with a box and cover of a hasp secured to one part and an arch secured to the other, and a block which encircles the arch and is therefore slidable on it, the width of the block being greater than the width of the aperture and the thickness of the block being less than the width of the aperture, the arch having 45 notches for permitting the block to be rotated to a position wholly in front of the aperture, the notches being located between the ends of the arch whereby when the block is at one end of the arch the block will be 50 nonrotatable and hence hold the hasp in locked position.

In witness whereof, I have hereunto subscribed my name.

AUGUST PITTELKOW.
